UNITED STATES PATENT OFFICE

DAVID S. HULFISH, OF CHICAGO, ILLINOIS, ASSIGNOR TO TELETYPE CORPORATION, OF CHICAGO, ILLINOIS, A CORPORATION OF DELAWARE

PRINTING TELEGRAPH SYSTEM

Application filed September 20, 1926, Serial No. 136,600. Renewed October 1, 1930.

This invention relates to systems in which intelligence is transmitted by electric signals arranged according to a predetermined code. Several codes are known and others may be devised.

The object of this invention is to translate electric signals arranged according to a code, such as the Baudot code, into other electric signals deemed more suitable for transmission, and then to re-translate the transmitted signals into the original code.

The manner of operating this invention is as follows: The groups of electric signals of the message, nominally "letter-groups" of signals according to the given code, are regrouped into translation-groups without taking cognizance of their significance. The translation-groups are translated into transmission-groups having greater facility in transmission than the original electric signals. The transmission-groups are transmitted, re-translated and re-grouped into a reproduction of the original letter-groups.

In the drawings, Fig. 1 shows a transmitting station, with five sets of translating relays indicated; Fig. 2 shows a receiving station with five sets of re-translating relays indicated; Fig. 3 shows the circuits of a set of translating relays; Fig. 4 shows the circuits of a set of re-translating relays; Fig. 5 shows the translation code as applied to the details of tape shown in Fig. 1.

The thirty-two signal combinations or letter-groups of the five-unit two-element code are shown in the following table, in which the columns are numbered 1 to 5 to identify the wires 1—A and so on, and the lines are numbered to identify the combinations. P indicates that the wire identified is earthed at the sender; N indicates that the wire is open at the sender contact.

Table I

1 2 3 4 5	1 2 3 4 5	1 2 3 4 5	1 2 3 4 5
1 NNNNN	9 NPNNN	17 PNNNN	25 PPNNN
2 NNNNP	10 NPNNP	18 PNPNP	26 PPNPP
3 NNNPN	11 NPNPN	19 PNNPN	27 FPNPN
4 NNNPP	12 NPNPP	20 PNPNP	28 FPNPP
5 NNPNN	13 NPPNN	21 PNPNN	29 PPPNN
6 NNPNP	14 NPPNP	22 PNPNP	30 PPPNP
7 NNPNN	15 NPPPN	23 PNPPN	31 PPPPN
8 NNPPP	16 NPPPP	24 PNPPP	32 FPPPP

Referring to Figs. 1 and 3, five sets of translating relays according to the area 101 of Fig. 3 are to be provided for the five areas, 101, 201, 301, 401, 501, to complete the circuits of Fig. 1. Three senders are indicated at R, S, T, sending five-unit code. When a tape such as 2—R is being "sent" by the sender R, a combination of the contacts of the sender R will be operated against the left-hand bus-bar according to the holes in the tape; for instance, the combination 29 of Table I will permit the contacts to connect earth to wires 1—A, 2—B, 3—C, but will estop earth from wires 4—A, 5—B. The energization of the sender magnet 3—R will lift the contacts from the earthed bus-bar and will step the tape to the next combination, 22 in tape 2—R.

When the sender R is closed upon a letter-group of holes in the tape 2—R a letter-group of electric signals will be placed upon wires 1—A, 2—B, 3—C, 4—A, 5—B. Where an open circuit is a signaling option, it is accounted that an open circuit is an electric signal within the meaning of this specification. Of these signals, the signals upon wires 1—A, 2—B, 3—C constitute a translation-group of electric signals, to be translated by the translating relays of the area 101. Wires 1—A, 2—B, 3—C will actuate the determined translating relays of the area 101, which will function by their points to place a transmission-group of electric signals of a three-element code upon the wires D and E, according to the following translation table. This condition will be continued, and the signals stored, until sender R functions again. The wires are identified by letters at the columns, and the combinations are identified by numbers at the lines, the two codes in any line being translatable, either into the other, by the translating relays of Fig. 3 or by the re-translating relays of Fig. 4. P indicates positive battery; N indicates negative battery; the sign # indicates an actuated relay; O indicates an open circuit or a non-actuated relay. Only eight pairs of combinations are possible.

45 4. P indicates positive battery; N indicates negative battery; the sign # indicates an actuated relay; O indicates an open circuit or a non-actuated relay. Only eight pairs of combinations are possible.

Table II

	A	B	C	D	E
41	O	O	O	N	N
42	O	O	O	N	G
43	O	O	O	G	N
44	O	O	O	G	P
45	#	O	O	P	N
46	#	O	O	N	P
47	#	#	O	P	G
48	#	#	#	P	P

Referring to the translation Table II and to Fig. 3:

- 10 The circuits of the translating relays, 71, 72, 73, may be traced as follows: Group 41, (OOO), no relay actuated; wire D through points of relays 72 and 71 to N; wire E through points of relays 73 and 72 to N; Group 51 (NN) is formed. Group 42 (OO#) relay 73#; wire D as in group 41, wire E through points of relay 73#, 72 and 71 to G; group 52 (NG) is formed. Group 43 (O#O) relay 72#; wire D through points of 15 relays 72# and 71 to G; wire E through points of relays 73, 72# and 71 to N; group 53 (GN) is formed. Group 44 (O##) relays 72#, 73#; wire D as in group 43; wire E through points of relays 73# and 72# to P; group 54 (GP) is formed. Group 45 (#OO) relay 71#; wire D through points of relays 72, 71# and 73 to P; wire E as in group 41; group 55 (PN) is formed. Group 46 (#O#) relays 71#, 73#; wire D through points of 20 relays 72, 71# and 73# to N; wire E through points of relays 73#, 72 and 71# to P; group 56 (NP) is formed. Group 47 (##O) relays 71#, 72#; wire D through points of relays 72# and 71# to P; wire E through points of 25 relays 73, 72# and 71# to G; group 57 (PG) is formed. Group 48 (###) all relays actuated; wire D as in group 47; wire E as in group 44; group 58 (PP) is formed.
- 30 In the distributor 60, the brush 63 in its motion connects line wire 64 to wire D and then to wire E, transmitting to the line wire 64 the transmission-group of signals set up by the translating relays of the area 101.

35 Sender R has determined the selective condition of the relays 71 and 72 of the area 201. Sender S has determined the condition of the relay 73 of the area 201; sender S has determined also the condition of all relays of the area 301 and of relay 71 of the area 401; two more translation-groups are completed in the areas 201 and 301 and the relays thus actuated translate those groups into transmission-groups of signals on wires D—2, 40 E—2, D—3, E—3, and brush 63 transmits 55 these signals to the wire 64.

When brush 63 reaches wire D—3, it has transmitted all signals dependent upon sender R, and sender magnet 3—R is energized over the path, battery, magnet 3—R, distributor contact 4—R, brush 62 and earth; sender R steps its tape and places the next letter-group of signals on wires 1—A to 5—B, thus actuating the translating relays in their next combination.

60 Sender T now has placed a letter-group of

signals upon wires 1—B, 2—C, 3—A, 4—B, 5—C, thus determining the selective condition of relays 72 and 73 in the area 401 and of all relays in the area 501, completing two more translation-groups. The translating relays 70 translate those groups into transmission-groups of signals upon the wires D—4, E—4, D—5, E—5, and brush 63 transmits those signals to wire 64. The brush 63 has completed one cycle of the apparatus shown. The 75 speed of the brush 63 and the electrical constants of the conductor 64 are not of the essence of this invention.

When brush 63 reaches wire D—5, it has transmitted all signals dependent upon sender S, and sender magnet 3—S is energized over the path, battery, magnet 3—S, distributor contact 4—S, brush 62 and earth. At the beginning of the next cycle, magnet 3—T is energized over the path, battery, magnet 80 3—T, distributor contact 4—T, brush 62 and earth. The cycle repeats indefinitely, with ever varying combinations in the senders R, S, T, resulting in continuous, integral, uniform transmission.

90 Referring to Fig. 2 and Fig. 4, five sets of re-translating relays, according to the area 102' of Fig. 4 are provided for the five areas, 102, 202, 302, 402, 502 of Fig. 2 to complete the circuits of Fig. 2. Wire D' is correlative to wire D, and so on. Wire A—1 is correlative to wire 1—A, and so on, running from points of the re-translating relays to further instruments, such as printers, R', S', T', correlative to the senders R, S, T.

95 Line relay 74 is "cable-type", holding its points open when not influenced by current from the line 64, and placing P (or N) battery upon its tongue when P (or N) battery is connected to wire 64 by brush 63. The 105 brush 65 moves in synchronism with the brush 63.

100 Each polar relay as 75 of the retranslating units has two holding windings, as 76 and 77 (Fig. 4), each holding winding being connected to one of the points of its polar relay and to the winding of the controlled neutral relay 81 or 82 and thence to the points of the relay 85 and to battery, providing a holding circuit for storing a received signal which may be released by the relay 85.

105 In operating, when the brush 63 has reached the wire D—3', the electrical signals upon wires D, E, D—2, E—2, have been transmitted and recorded upon the re-translating relays of areas 102 and 202, those relays have 110 re-translated the two transmission-groups into a reproduction of two translation-group signals, now upon wires A—1, B—2, C—3, A—4, B—5, and C—1. Five of these wires, A—1 to B—5, are re-grouped by effect of their common destination in the printer R', and the five electrical signals upon those wires thus are re-grouped and constitute a 115 reproduction of the letter-group of electrici- 120 125 130

cal signals set up by the sender R. Printer-starter magnet 5—R now is energized over a circuit including battery, magnet 5—R, distributor-contact 6—R, brush 66 and earth.

5 At the same time, the re-translating relays of areas 402 and 502 are released by the operation of relay 85—T energized over a circuit including battery, winding of relay 85—T, contact 6—R, brush 66 and earth.

10 When the brush 65 has reached the wire D—5', the signals of wires D—3, E—3, D—4, E—4, have been transmitted to the relays of the areas 302 and 402 and have been re-translated from the transmission-group signals into a reproduction of the translation-group signals. By their destinations, the translation-group signals have been re-grouped to complete the letter-group of signals upon printer S', and to begin a letter-group of signals upon printer T'. Brush 66 now places earth upon contact 6—S which energizes relays 5—S and 85—R, the former to start the printer S' and the latter to release the relays of the area 102.

25 When the brush 65 has passed wire E—5', the signals of wires D—5 and E—5 have been transmitted to wires D—5' and E—5' and have been re-translated by the relays of area 502. The reproduced translation-group signals have completed the letter-group of signals upon the printer T'. At the beginning of the next cycle, brush 66 places earth upon contact 6—T, which energizes relays 5—T and 85—S, the former to start the printer 30 T' and the latter to release the relays of areas 202 and 302, none of which is involved in the letter-group now upon the printer T'.

The manner of re-translation is as follows, referring to the translation table and to Fig. 4:

45 When a negative (N) signal is received on wire D', relay 75 is actuated by N battery and its armature moves right. Relay 75 closes a circuit from battery through points of relay 85, wire F, winding of re-translation relay 82, holding-winding 77 of relay 75, points of relay 75 and earth. Relay 82 is actuated and both relays 82 and 75 are held. In like manner, a P signal on wire D' actuates and holds relays 81 and 75; a P signal on wire E' actuates and holds relays 83 and 78; and an N signal on wire E' actuates and holds relays 84 and 78.

The circuits of the re-translating relays, 50 51, 82, 83, 84, may be traced as follows: Receiving group 51 (NN) relays 82#, 84#; wire A through points of relays 81, 82# and 83 to wire 80 which will be N or open as required by the mechanism of the printer served by it; wire B through points of relays 81 and 82# to wire 80; wire C through points of relay 84# to wire 80; group 41 (OOO) is formed on wires A, B, C. When receiving group 52 (NG), relay 82# only; wires A and 55 B as in group 51; wire C through points of

relays 84, 83 and 82# to wire 79, which is connected to earth or to positive battery as required by the printer served by it; group 42 (OO#) is formed. When receiving group 53 (GN) relay 84# only; wire A through points of relays 81 and 82 to wire 80; wire B through points of relays 81 and 82 to wire 79; wire C as in group 51; group 43 (O#O) is formed. When receiving group 54 (GP) relay 83# only; wires A and B as in group 53; wire C through points of relays 84 and 83# to wire 79; group 44 (O##) is formed. When receiving group 55 (PN) relays 81# 84#; wire A through points of relay 81# to wire 79; wire B through points of relays 81# and 84# to wire 79; wire C as in group 51; group 45 (#OO) is formed. When receiving group 56 (NP) relays 82# and 83#; wire A through points of relays 81, 82# and 83# to wire 79; wire B as in group 51; wire C as in group 54; group 46 (#O#) is formed. When receiving group 57 (PG) relay 81# only; wire A as in group 55; wire B through points of relays 81# and 84 to wire 79; wire C through points of relays 84, 83 and 81# to wire 80; group 47 (##O) is formed. When receiving group 58 (PP) relays 81# and 83#; wire A as in group 55; wire B as in group 57; wire C as in group 54; group 48 (###) is formed.

Referring to Figs. 1, 2 and 5. In Fig. 1 are tapes 2—R, 2—S, 2—T. Assume that the first cycle of brush 63 is made when the senders R, S, T, all three are sending the letter-group 29 Table I which appears on the three tapes, and that on the next cycle the senders send letter-groups 22, 22, 17. The resultant currents over wires 1—A to 5—C are represented by the black rectangles on the line 86 of Fig. 5. These signals are grouped at the senders into letter-groups, six groups of five signals each, by effect of their source of origin, as indicated by the numbers above line 86. The signals are re-grouped by effect of the destinations of conductors 1—A to 5—C, into translation-groups, ten groups of three signals per group, as indicated by the numbers below the line 86. By the translation relays, the translation-groups translated into the transmission-groups which are indicated on the line 87. These are as follows:

58 52 57 54 55 56 54 53 57 51
PP NG PG GP PN NP GP GN PG NN

The signals of the transmission-groups are transmitted, and are re-translated into a reproduction of the translation-groups upon the wires A—1 to C—5, in ten groups of three signals per group by effect of their source of origin in the re-translation relays, the groups being as indicated by the numbers above the line 88. The signals are represented by the black rectangles upon the line 88. These signals then are re-grouped by effect of the destination of the conductors A—1 to

C—5, into six groups of five signals per group, as indicated by the numbers below the line 88, and thus they constitute a reproduction of the original letter-groups of electrical signals as created by the senders R, S, T.

Having thus described my invention, what I claim is:

1. In a printing telegraph system, a plurality of senders, each sending signals in letter-groups; a plurality of sets of translating relays; conductors connecting said senders and said sets of relays whereby the signals received from said senders in letter-groups are distributed to said relay sets in regrouped form as translation-groups, the translation-groups thus formed being smaller in size and greater in number than the letter-groups; and circuits in said relay sets for translating the signals of the translation-groups into another arrangement of signals.
2. In a printing telegraph system, a sender adapted to create electrical signals according to a first code and in letter-groups; a plurality of sets of translating relays, each set adapted to receive and to store a fractional part of the signals of a letter-group; each relay set adapted to translate the stored signals into a different number of signals according to a second code and independently of the remaining signals of the letter group.

3. In a printing telegraph system, senders for sending signals in letter-groups; sets of signal-storing and translating relays; means for distributing the signals from said senders to said relay sets in such manner that a single relay set may receive signals from each of two letter-groups; and circuits in said relay sets for translating the signals into another system of signals.

4. In a printing telegraph system, a plurality of senders for sending signals in letter-groups and adapted to send a plurality of letter-groups simultaneously thereby to produce a group of simultaneous signals equal in number to the number of senders multiplied by the number of signals in a letter-group; a plurality of translating devices each adapted to translate simultaneous signals in translation-groups of different size from the letter-groups, said translating devices being provided in sufficient quantity to receive simultaneously the total of simultaneous signals sent by said senders; and conductors joining said senders and said translating devices and arranged in such system that the letter-grouping of signals is ignored and the total signals are assigned to the total translating devices in translation-groups of desired size, the number of unit signals in a translation group being incommensurate with the number of unit signals in a letter group.

5. In a printing telegraph system, senders for producing signals in groups of convenient printing size; a distributing system

for re-grouping the signals into groups of convenient translation size; translation devices for storing the signals and for reducing the number of signals for transmission; means for transmission; re-translation devices for restoring the original signals; and a re-distribution system for re-grouping the restored signals into a reproduction of the original groups of convenient printing size.

6. In a printing telegraph system; senders for sending signalings in letter-groups of five signals each; distributing conductors grouped at one end in groups of five and at the other end in groups of three; a plurality of sets of translating relays for translating groups of three signals each into groups of two signals each; a sending distributor, a line and a receiving distributor co-operating to transmit the transmission-groups of two signals each to sets of re-translating relays; said sets of re-translating relays for re-translating said groups of two signals into groups of three signals each; a plurality of printers operable in response to letter-groups of five signals per group; and other distributing conductors running from said re-translating relays to said printers and grouped at the relay end in groups of three and at the printer-end in groups of five, thereby reproducing the groups of signals in letter-groups as sent by the said senders.

7. In a printing telegraph system, a set of relays adapted to receive and store a combination of three electrical signals in predetermined permutation of two-element code and in response thereto to set up on its contact points a combination of two electrical signals in a permutation of a three-element code; another set of relays adapted to receive and store the mentioned combination of two electrical signals of a three-element code and in response thereto to set upon its contact points the combination of three electrical signals as received by said first-mentioned set of relays; the said contact points; a line; and two distributors, said line and distributors connecting said sets of relays.

8. In a printing telegraph system, means for producing a continuous sequence of electrical signals at a constant, uniform speed and arranged according to a code; sets of translating relays adapted to receive signals and to store signals in groups; and a distributor cooperating with said sets to put out a continuous sequence of a smaller number of signals arranged according to a different code.

9. In a printing telegraph system, a plurality of signal senders producing unit signals at a uniform rate, a set of signal translators storing the unit signals from said senders and translating to another code of fewer unit signals, a sending distributor sending a continuous sequence of signals from said set of translators, a line wire, a receiving dis-

tributor, a set of signal translators receiving a continuous sequence of unit signals from said receiving distributor and storing the unit signals in groups and translating them 5 in groups into suitable printing signals, and a plurality of printers, said senders, said distributors and said printers operating at uniform speeds separately and relatively and operating together as a synchronous-multiplex telegraph system and producing continuous, uniform-speed transmission.

10. In a printing telegraph system, relays, contact points in said relays; the said relays being adapted to receive and store a combination 15 of three electrical signals in any predetermined permutation of two-element code and in response thereto to set up on their said contact points a combination of two electrical signals in a corresponding permutation 20 of a three-element code; means co-operating with said contact points to transmit the two signals; and re-translating means for receiving the two signals and for reproducing the signals first mentioned.

25. 11. In a telegraph system, means for producing a continuous sequence of electrical signals and arranged according to a code, means to store said signals in groups, and means to transmit under control of the stored 30 signals a second sequence of smaller number signals arranged according to a different code.

35. 12. In a system for the transmission of code messages, each message being divided into a plurality of letter groups of code signals; a plurality of transmitters; and a plurality of signal storing and translating devices greater in number than said transmitters, each such signal storing and translating 40 device adapted to store a plurality of unit signals fewer than the number of unit signals in a letter group; some of said signal storing and translating devices being adapted 45 to receive and translate parts of separate code signals from a plurality of said transmitters.

50. 13. In a system for the transmission of code messages, each message being divided into a plurality of letter code groups of signals; a plurality of transmitters; a plurality of signal storing and translating devices greater in number than said transmitters; some of said devices being adapted to receive, store and translate into a different code system a 55 part of a letter code group of signals from one of said transmitters and some of said devices being adapted to receive, store and translate into a different code system parts of letter code groups of signals from a plurality 60 of said transmitters; and further transmitting means for transmitting the translated signals.

65. 14. The method of translating telegraphic code messages to facilitate transmission which comprises dividing the message into a

plurality of electrical signals of letter groups, dividing each letter group into separate predetermined parts, and storing and translating into fewer unit signals said separate parts in regrouped manner for transmission. 70

15. In a multiple channel system, the method of transmitting telegraphic code messages comprising the steps of generating code signals for each channel; combining parts of successive code signals from different channels in separate groups; translating each separate group into fewer unit signals per group and transmitting signals in accordance with the separate translated groups. 75

16. The method of grouping code signals 80 for the purpose of translating from one code to another in which the time intervals per letter in one code are incommensurate with the time interval per letter of the other code, which comprises providing groups for translation purposes which contain an integral number of complete signals in each group to make the total numbers commensurate. 85

17. The method of grouping code signals 90 for the purpose of translating from one code to another, in which the time intervals per letter of one code are incommensurate with the time interval per letter of the other code, which comprises, providing for translating purposes, groups of unit time intervals of 95 such numbers in each code that the two numbers are commensurate.

18. In a multiple channel telegraph system, the method of operation comprising steps of generating code signals for each 100 channel in accordance with independent messages to be transmitted thereover; combining parts of successive code signals from different channels in separate groups of unit signals translating each such group separately into fewer unit signals for transmission; transmitting signals in accordance with the separate translated groups; receiving and re-translating the groups into code signals of the character originally generated, and 110 distributing the code signals to receivers in separate receiving channels. 105

19. In a multiple channel telegraph system, the method of operation comprising steps of generating permutation code signals 115 for each channel in accordance with independent messages to be transmitted thereover, combining parts of successive code signals from adjacent channels in re-grouped form for translation, translating each such group of original unit signals into a different number of unit signals for transmission; transmitting signals in accordance with the re-grouping thus effected; receiving and re-translating the transmitted signals into the 120 permutation generated, and distributing the re-translated permutation code signals in proper order to receivers in separate receiving channels. 125

20. The method of operating a multiple 130

channel telegraph system comprising the steps of generating permutation code signals for each channel in accordance with independent messages to be transmitted there-over, re-grouping parts of successive code signals from different channels and storing the re-grouped signals; translating the stored signals group by group into a different number of unit signals transmitting signals in accordance with the stored groups; receiving and re-translating the group into the permutation code signals originally generated; storing the re-translated code signals; and distributing the stored code signals in proper order to receivers in separate receiving channels.
